M. J. KERMER

CENTRIFUGAL EVAPORATOR

Filed Jan. 16, 1925

UNITED STATES PATENT OFFICE.

MARTIN J. KERMER, OF CHICAGO, ILLINOIS.

CENTRIFUGAL EVAPORATOR.

Application filed January 16, 1925. Serial No. 2,773.

This invention relates to improvements in rotatable evaporators and it is one object of this invention to provide an effective seal to prevent the steam which is used for heating purposes from entering the interior of the evaporator or coming in contact with the packing that is used in connection with the bearings of the evaporator.

This invention is an improvement of the evaporator shown in my co-pending application, Serial No. 700,508, filed March 20, 1924. One distinguishing feature herein disclosed is the means for sealing the steam in the steam jacket which encompasses the rotatable cylinder within which concentration is effected.

Another new feature is the means for preventing a hydrostatic head due to steam condensation within the confined space surrounding the aforesaid cylinder by not rotating the steam and water jacket or housing.

The invention furthermore comprises the novel structure and combinations of elements hereinafter described and more particularly pointed out and defined in the appended claims.

In the accompanying drawings which illustrate a preferred embodiment of this invention and in which similar reference numerals refer to similar features in the different views:—

Figure 1 is an elevational view of the evaporator for disclosing this invention.

Figure 2 is an enlarged fragment part in section and part in elevation illustrating this invention.

Figure 3 is an enlarged fragmentary sectional view taken substantially on the line 40 3—3 of Figure 2.

Figure 4 is an enlarged sectional view through the sealing chamber.

Figure 5 is a reduced sectional view of a part of the side wall of the steam jacket or housing showing the method of admitting steam into the annular steam receiving space.

As shown on the drawings:

There is a rotatable cylinder 1 which is mounted in suitable bearings that surround it and that are supported by a suitable fixed steam jacket or housing 2.

Between the lower part of the cylinder and the jacket or housing 2 there is a confined cylindrical steam receiving chamber 3. The section 2^a of the jacket or housing at the upper end of the steam chamber has a radi-

ally extending flange 2^b. The next upper adjacent section 2^c of the housing rests upon the flange 2^b and is provided with an annular inwardly spaced flange 2^d whereby an 60 annular liquid receiving chamber 4 is formed. The rotating cylinder 1 is provided with a radial depending flange or lip 5 that extends into the chamber 4 and that is slightly spaced from the interior surface of 65 the housing section 2^c. The upper interior surface of the housing section 2^c is rabbeted and a wedge shaped baffle ring 6 rests upon the shoulder formed by the rabbet of said housing section. 70

The wall of the rotating cylinder 1 is threaded and is slightly reduced upon its exterior surface just above the inner edge of the baffle ring 6, another baffle ring 7 rests upon the shoulder formed by said reduced 75 portion and is rotatable with the cylinder 1. The lower surface of this baffle ring 7 slopes upwardly and outwardly, which is oppositely to the adjacent slope of the ring 6 with which it is adapted to co-act. The upper 80 surface of the baffle ring 7 is horizontal and forms a support for a felt packing ring 8 or the like. There is a narrow space between the baffle rings.

A bearing ring 9 rests upon the flange 2^d 85 and is contained between the flange 2^d of the housing section 2^c and the flange 2^e of the housing section 2^f, the portion of the ring between said flanges being reduced or rabbeted upon both sides. 90

A bearing ring 10 having an upper sloping surface rests upon the ring 9 and radially movable segments or arcuate blocks 11, having lower bevelled surfaces, rest upon the ring 10, each block has a threaded aperture 95 for adjustably receiving an adjusting bolt 12 which extends through the housing section 2^f in the plane of the flange 2^e which is provided with suitable grooves 13 in alinement with said bolts when the blocks 11 are 100 drawn outwardly by bolts 12, ring 16 is raised into closer approximation with ring 15 and thus adjustment to compensate for wear of the bearing parts is made.

Spaced above the ring segments or arcuate blocks 11 there is a ring 14 which is threaded on and rotates with the cylinder, and a ball bearing structure 15—16—17 is confined between the arcuate blocks 11 and said ring 14. This ball bearing structure 110 contains an upper race member 15, which rotates with the cylinder 1, a lower stationary

race member 16 and intermediate bearing balls 17.

A rotatable angular ring 18 is confined in the housing section 2^a located above the ring

5 14. The adjustment of the screws 12 will obviously adjust the ball bearing structure.

The bearing ring 7 does not extend to the wall of the housing section 2^a, a small space being left for adjustment and a duct 19 extends from said ring through the flange 2^a of said housing section. Likewise a duct 20 extends from the chamber 4 through the housing section 2^a. A glass tube 21 communicates with these ducts through suitable tubes 22 and 23 threaded into said ducts.

10 A liquid such as mercury 24 or the like is placed within and remains in the chamber 4 and its height may be observed thru the glass tube, which also forms a depository for grease or other matter that may find its exit through the upper duct 19.

15 It is well known that such evaporators rotate at a high rate of speed and may develop on a confined liquid by centrifugal force a resistance which may be of considerably greater effect than the steam pressure in the steam chamber 3. Consequently the pressure of the steam on the mercury in the mercury chamber 4 will not be able to expel or force the mercury therefrom between the flange 5 and housing section 2^a on account of the resistance of the confined liquid effected by the centrifugal force, and as the mercury operated on by centrifugal action provides an efficient seal, the steam cannot permeate therethrough. To do so the steam pressure would have to force the mercury thru the annular space between 2 and 5 radially toward the axis of the rotating cylinder and against the effect produced by centrifugal action which tends always to compact the mercury and to force it in the opposite direction, so it is impossible for the steam to escape through the mercury seal 20 through bearings and enter the top of the cylinder which is operating at sub-atmospheric pressure and interfere with the action in the evaporating chamber.

25 In Figure 5, 2 is a sectional view of the stationary housing wall 2^a thru which steam is admitted into the steam receiving space 3. The steam conveying pipe 25 extends parallel with the jacket or housing 2^a and branches 26 connect the steam pipe at intervals to permit steam to enter space 3 at a plurality of localities to more uniformly distribute the heat to the cylinder 1.

30 The condensed steam or water in the space 3 will be thrown outwardly by the centrifugal effect of the cylinder 1 into contact with the inner surface of the wall 2^a where it will entrain and be trapped out by effect of gravity thru opening 35. As the water is not materially rotated an objectionable 35 hydrostatic head will not be formed in space

3, therefore full heat interchange will be effected with the rotating cylinder.

The cylinder 1 is rotated by shaft 27 by pulley 28.

The device is shown in position with its 70 longest axis in a vertical plane and supported on a frame 29.

The cylinder may be exhausted thru pipe 30 secured in the head 31. Steam will enter pipes 26 and be projected into contact 75 with the outer surface of the rotating cylinder 1 in radial planes. The movement of the cylinder past the impacts of the steam jets will remove or wipe away any water or steam film from the surface of the rotating cylinder, therefore there will not be interposed between the steam and the cylinder any insulating films that are usually formed and the steam will have intimate 80 contact with the cylinder surface.

85 I am aware that many changes may be made, and numerous details of construction may be varied through a wide range without departing from the principles of this invention, and I therefore do not purpose 90 limiting the patent granted hereon, otherwise than necessitated by the prior art.

95 I claim as my invention:—

1. In an evaporator, a rotatable cylinder, a stationary housing in spaced and concentric relation with said cylinder, a portion of said cylinder and housing providing a steam chamber, and a portion of said housing providing an annular fluid chamber near the end of said steam chamber to seal the chamber, and bearings between said housing and cylinder beyond said fluid chamber.

100 2. In an evaporator, a housing having a steam chamber and a fluid chamber above said steam chamber, a rotatable cylinder in said housing having an annular depending flange positioned in said fluid chamber adjacent the outer wall thereof providing an inwardly directed path for said fluid, the centrifugal force when the cylinder is rotated 105 preventing the escape of fluid thru said path.

110 3. In an evaporator, a rotatable cylinder, a housing spaced from and concentric with said cylinder, said cylinder and housing providing a steam chamber and said housing having a fluid chamber beyond said steam chamber, said cylinder having means extending into proximity of the outer wall of said fluid chamber providing a path for the fluid extending inwardly toward the axis 115 of rotation of said cylinder.

120 4. In a device of the class described, a housing having an annular interior fluid chamber; a rotatable cylinder journaled in said housing and having an annular and depending annular flange within said fluid chamber and adjacent the outer wall thereof providing a path therefrom toward the axis of the cylinder.

125 5. In an evaporator, a rotatable cylinder,

- a housing concentric with but spaced from said cylinder to provide an annular space between said housing and cylinder, extending toward the rotatable axis of the cylinder, bearings located in the upper part of said space, a steam chamber in the lower part of said space and an intermediate liquid seal controlled by the centrifugal force caused by rotation of said cylinder.
10. 6. In a device of the class described, a stationary cylindrical member having an interior annular fluid chamber opening upwardly and inwardly, a rotatable member within said cylindrical member, said rotatable member having an annular depending flange extending into said fluid chamber adjacent the outer wall thereof to provide a seal.
7. In a rotatable evaporator, a seal for 20 fluid under pressure, comprising a stationary member having an annular groove, a member rotatable upon a vertical axis, an annular flange extending from said rotatable member into said groove near the outer 25 wall of said groove leaving an annular passage along the outer surface of said flange, and a liquid in said groove to provide a seal when the rotatable member is rotated.
8. In a rotatable evaporator, a seal for a 30 member thereof rotatable on a vertical axis, a relatively stationary member providing an annular groove containing a liquid, said members providing a space to contain a fluid under pressure in communication with said 35 groove, and a passageway from said groove for said liquid extending toward the axis of said rotatable member.
9. A centrifugal evaporator comprising a 40 cylinder rotatable on a vertical axis; a surrounding stationary jacket to provide a steam receiving space about said cylinder and means to introduce steam at a plurality of vertical intervals into said steam space in paths radial to the axis of said cylinder, whereby to produce direct impacts of jets of steam against said rotating surface.
10. A pressure-resisting seal for relatively 45 rotatable members comprising an outer member having an annular groove to contain a liquid; an inner member having an annular part insertible in said groove to provide an axially converging annular path between the parts and extending from said groove and a liquid in said groove to form a pressure resisting seal by effect of centrifugal action when one of said members is rotated.
11. A pressure-resisting seal for relatively 50 rotatable members comprising an outer member having an annular open groove to contain a liquid; an inner member having a 55 part insertible into said groove to provide an axially extending and an axially converging annular path for the liquid from said groove and between said parts and a liquid in said groove held in said path by centrifugal action when one of said members is rotated.
12. A pressure-resisting seal for relatively 60 rotatable members comprising an outer member; an inner member; an annular groove 65 between the members to contain a liquid; an annular flange provided by one of said members extending into said groove to provide an axially converging annular path between said flange and the wall of the groove and a 70 liquid in said groove and path operating as a pressure seal between the members by effect of centrifugal action when one of said members is rotated.
- In testimony whereof I have hereunto sub- 75 scribed my name.

MARTIN J. KERMER.
